(57) **CLAIM**

The ornamental design for a miniature LED bulb, as shown and described.

DESCRIPTION

FIG. 1 is an isometric view of the miniature LED bulb, embodying the claimed design;

FIG. 2 is a front plan view thereof;

FIG. 3 is a rear plan view thereof;

FIG. 4 is a right plan view thereof;

FIG. 5 is a left plan view thereof;

FIG. 6 is a top-down plan view thereof; and,

FIG. 7 is a bottom-up plan view thereof.

The portions shown in broken lines are not part of the claimed design but show the environment in which the design is associated.
